OIL BURNER BLOWER HOUSING

Ernest Camerino, New York, N. Y.

Application May 14, 1947, Serial No. 748,089

7 Claims. (Cl. 230—114)

1

This invention relates to oil burners and more particularly to an improved oil burner blower housing.

The invention provides improvements upon the blower unit disclosed and claimed in my Patent No. 2,095,230, issued October 12, 1937.

An object of the invention is to provide a compact blower housing having a longer air path travel between the discharge of the air fan or impeller and the entrance to the blast tube without increasing the overall length of the burner.

Another object of the invention is to provide a blower housing having an upper semi-cylindrical impeller section and a lower rectangular section integrally formed with the impeller section, such rectangular section being divided by a partition into two separate air chambers, and at least one intermediate air chamber disposed on the side of the rectangular section for establishing an air-communicating passage between said two chambers.

Another object of the invention is to provide a compact burner housing which supplies a turbulent air stream of relatively low velocity to a relatively short blast tube; such stream mixing and burning with an atomized spray of oil to produce a relatively quiet flame of desired shape.

A further object is to provide a compact burner housing having an automatic damper, on the discharge side of the air impeller or fan, and preferably in the intermediate chamber, for regulating the pressure, or the maximum flow of air, or both, during an operative burner period, and for preventing the flow of a natural chimney draft through the burner housing during an inoperative burner period.

Other objects and novel features will become apparent from the following description and accompanying drawings, in which:

Fig. 1 is a side elevational view, partly in section, of an oil burner blower housing embodying the features of this invention;

Fig. 2 is a rear elevational view, partly in section, taken from the left of Fig. 1; and

Fig. 3 is a plan view along the line 3—3 of Fig. 1.

With reference to Fig. 1, the blower housing H comprises an upper semi-cylindrical impeller portion 10 having downwardly converging front and rear walls 12 and 14, respectively; and substantially parallel side walls 16 and 18, respectively. A rectangular bottom wall 20, integrally formed with the side, front and rear walls, forms a lower closure for the housing and such bottom wall is rigidly secured to the base B by an adjustable support 22. The semi-cylindrical portion 10 houses a conventional air impeller or fan (not shown). An electric motor housing 24 is disposed substantially in axial alignment with the longitudinal axis of the semi-cylindrical portion 10. On the side of the housing H, opposite to the

2

motor housing 24, is located a cylindrical air-intake section 26, also substantially in axial alignment with the motor axis 24. Adjustable air-intake ports 28 may be disposed, if desired, in the lower portion of housing 26.

A central vertical baffle 30 located in a plane parallel to the front and rear walls 12 and 14 is disposed within the housing H. The upper portion of the baffle forms a seal with a curved wall 32 (partially shown), which latter joins the forward wall 12 of the housing, while the lower portion of the baffle 30 forms a seal with the base 20. Thus, the baffle effectively divides the housing H into two separate air chambers, a rear air chamber 34, and a forward air chamber 36; the former receives air from the impeller section 10 while the latter communicates with a blast or discharge tube 38.

The side wall 18 is provided with a rectangular opening 39 which is substantially equally spaced with respect to the front and rear chambers 34 and 36. A closure member 40, preferably box-like in shape, is disposed over the opening 39 to form a lateral air passage or intermediate chamber between the front and rear chambers. As shown in the drawings, this box-like member is of a size sufficient to offer no substantial resistance to a stream of air flowing therethrough, yet it provides a considerable increase in the length of travel and turbulence of such stream.

A damper D is pivotally hinged about a pin 42, horizontally disposed across the top of the entrance to the auxiliary box-like chamber 40 and such damper is adapted to swing upwardly, as shown in the drawings, during an operative period, and to close downwardly against pin 41 during an inoperative period. If desired, limiting means, such as a screw 44, may be provided in the upper part of the intermediate chamber to control the extent of the opening of the damper D, and thereby control the shape or combustion efficiency of the flame. Adjustment of screw 44 may be effected while the burner is in operation, thus permitting quick and ready flame regulation. A set or lock nut 46 or similar means may be used to fix or set the screw 44 in a desired position.

In order to insure proper closing of the damper during an inoperative burner period, as well as to provide control of the pressure of the air supplied to the blast tube during an operative burner period, a threaded extension 47, having a weight nut 48 thereon, is disposed on the air-discharge side of the damper D. The threaded extension 47 is disposed in a direction at right angles to the pin 42. Adjustment of the nut 48 along the threaded extension permits regulation of the weight of the damper and also the regulation of the force of the air required to lift said damper, i. e., by moving the nut 48 in a direction away from the pin 42, the closing force increases, while

adjustment in the reverse direction decreases the closing force. During an inoperative burner period, the weight nut 48 assists in urging the damper to a closed position, thereby preventing the movement of air into the fire box. During an inoperative period of a conventional oil burner, the hot combustion zone in the boiler or furnace has a tendency to create an induced draft through the burner and if this draft is not checked, the combustion zone is chilled and poor flame combustion usually occurs when the burner is restarted. However, this difficulty is overcome by the gravity-operated damper in the housing of the present invention.

During normal operation, air is drawn by the impeller through the intake openings 28 and is forced by the fan impeller downwardly into the rear chamber 34. After striking the bottom of the latter, it flows laterally, lifting and flowing under the damper D, and strikes the rear wall of the intermediate chamber 40, whereupon it reverses its direction of flow and enters the forward chamber 36. In this forward chamber, further turbulence is created in the air stream when the latter strikes side wall 16. Thus the air entering the blast tube 38 has a maximum degree of turbulence, a minimum velocity, and is remarkably free from impeller pulsation effects. In addition, due to the relatively long length of air travel and the large cushioning effect of the three air chambers, a very uniform flow of air is introduced into the blast tube. Thus, the burner housing, in a relatively short overall height and length, has a relatively long air travel path. A comparatively short blast tube may be used, thus permitting the burner housing to be positioned closer to a furnace or to a boiler than with conventional types of burners. In this way, the blower housing and blast tube may be enclosed in a modern cabinet.

While certain embodiments of the invention have been illustrated and described, it will be obvious to those skilled in the art that the invention may be otherwise embodied and practiced without departing from the principles or scope thereof.

I claim:

1. In an oil burner blower housing, the combination of an upper impeller section; a substantially rectangular lower section integrally formed with said impeller section; means for dividing the lower section into two separate air chambers; and an intermediate chamber laterally disposed on the side of said lower section for providing air communication between said two chambers.

2. An oil burner blower housing, comprising an upper impeller section; a lower section having a blast tube connected thereto; a pair of air chambers within said lower section, one of said chambers being constructed and arranged to receive air from said impeller section, and the other of said chambers being constructed to discharge air into said blast tube; and an intermediate chamber laterally offset on the side of said lower section for establishing air communication between said chambers.

3. In an oil burner blower housing for supplying a turbulent stream of air to a blast tube, the improvement comprising an upper semi-cylindrical impeller section; a lower rectangular section containing a substantially rectangular rear chamber for receiving air from said impeller section and a substantially rectangular forward chamber,

located adjacent to said rear chamber, for discharging air to said blast tube; and an intermediate rectangular chamber laterally offset on a side of said lower section for receiving air from said rear chamber reversing the direction of flow of such air and introducing it into said forward chamber.

4. In an oil burner blower housing for supplying a stream of air to a blast tube, the improvement comprising an upper semi-cylindrical impeller section; a lower rectangular section integrally formed with said impeller section and containing a first chamber for receiving air from said impeller section, and a second chamber separate from said first chamber for discharging air to said blast tube; and an intermediate chamber laterally disposed on an exterior wall of said lower rectangular section for receiving air from said first chamber and for introducing air into said second chamber.

5. In an oil burner blower housing, comprising an upper horizontally disposed semi-cylindrical impeller section; a base; downwardly converging front and rear walls extending from the cylindrical surface of said impeller section to said base; a blast tube connected to said forward wall; substantially parallel side walls extending from the ends of said semi-cylindrical impeller section to said base; a vertical baffle within said housing interconnecting said side walls and forming two air chambers with said front and rear walls, and said base; and an intermediate chamber disposed in at least one side wall for providing an air passage around said baffle between said two chambers.

6. In an oil burner blower housing comprising an upper impeller section, a plurality of air chambers disposed directly beneath said impeller section, and a gravity-responsive damper in at least one of said chambers, said damper being arranged and constructed to control the pressure and maximum flow of air during an operative burner period, and automatically to stop the flow of natural inducted draft through said housing during an inoperative burner period.

7. In an oil burner blower housing, the combination of an upper semi-cylindrical impeller portion having its longitudinal axis disposed horizontally, a lower rectangular portion integrally formed with said impeller section, two separate air chambers in said lower rectangular portion, a blast tube connected to one of said chambers, an intermediate chamber disposed on the side of said lower rectangular portion; a weight-responsive damper in said intermediate chamber, means for regulating the maximum opening of said damper, and weight-responsive means for closing said damper during an inoperative burner period.
